UNITED STATES PATENT OFFICE.

ALEXANDER W. FARCUS AND DAVID T. JACOBS, OF PHILADELPHIA, PENNSYLVANIA.

BRUSH HOLDER FOR COMMUTATORS.

Application filed December 5, 1924. Serial No. 754,048.

To all whom it may concern:

Be it known that we, ALEXANDER W. FARCUS and DAVID T. JACOBS, citizens of the United States, residing at Philadelphia, county of Philadelphia, and State of Pennsylvania, have invented certain new and useful Improvements in Brush Holders for Commutators, of which the following is a specification.

10 Our invention relates to brush holders for commutators and more particularly to those known as the open type which have minimum sliding surface.

15 The open type of commutator brush holder and brush is universally used and accepted because dust and grit cannot accumulate to cause the brush to stick. The objection to this type is that the brush is free to shift and tilt sidewise so as to cause 20 uneven wear on the brush and commutator and thereby enhance the danger of the brush slipping out of position and causing serious injury to the dynamo or motor.

25 Another objection to this type is that when the commutator wears, the brush depends so far from the holder that the friction between the brush and the commutator causes the brush to cant or tilt out of position, thereby causing short circuiting and 30 burning of the electrical parts. To replace the brush holders with larger ones that extend to a point near the surface of the worn commutator so that the brush will not tilt out of position, is very costly.

35 The objects of our invention are to provide means on a brush holder which will prevent the brush from shifting or tilting sidewise, and which may be adjusted to the proper working position as the commutator 40 wears, thereby avoiding the uneven wear on the brush and commutator and the costly replacement of brush holders.

45 These objects, and other advantageous ends which will be described hereinafter, we attain in the following manner, reference being had to the accompanying drawings in which

50 Figure 1 is a vertical section through a brush holder having my invention applied thereto, certain of the parts being shown in full,

Figure 2 a view similar to Figure 1, illustrating the parts in another position,

Figure 3 a section on line 3—3 of Figure 1,

Figure 4 a perspective view of an element which forms a part of my invention, and

Figure 5 a perspective view of a brush made in accordance with my invention.

Referring to the drawings, 1 indicates a 60 commutator, 2 a brush holder mounted on the usual bar 3, and 4 a brush slidably held by the holder in engagement with the commutator. The holder has a bracket 5, a spring-pressed arm 6 pivoted thereto at 7 65 and a plate 8 mounted on the bracket for adjustment toward and from the commutator. The plate 8 is rigidly held in adjusted position by teeth 9 on the bracket meshing with corresponding teeth 9^a on the 70 plate and screws 10 passing through slots 11, in the plate, into the bracket. Brush 4 slidably engages the outer face of the plate and is held against the commutator by spring-pressed arm 6 engaging its upper 75 face, and against sidewise tilting or shifting by a guiding rib 12 on the plate fitting within a groove 13 in the brush.

In operation, the guiding rib 12 will keep the brush in proper vertical alignment to 80 cause even wear on the brush and commutator and thus lengthen the usefulness of the brush and the life of the commutator. As the commutator wears, plate 8 is adjusted toward the commutator as shown in 85 Figure 2, and thus prevents the brush from being canted and slipped out of position by the friction between it and the commutator. Plate 8 is adjusted by loosening screws 10 and bringing it down to the proper position 90 so that the teeth on the plate will mesh with the teeth on the bracket, after which the screws are tightened to hold the plate in adjusted position.

When a brush holder and brush as above 95 described are used, the possibility of the brush getting out of proper alignment and slipping out of position is eliminated and the costly replacement by larger brush holders is avoided.

100 While we have described our invention as taking a particular form, it will be under-

stood that the various parts may be changed without departing from the spirit thereof, and hence we do not limit ourselves to the precise construction set forth, but consider 5 that we are at liberty to make such changes and alterations as fairly come within the scope of the appended claims.

Having thus described our invention, what we claim as new and desire to secure by 10 Letters Patent is:—

1. A brush holder for commutators having a brush engaging face; a brush slidably engaging the face and the commutator, and a rib on the face for guiding the brush 15 toward and from the commutator.
2. A brush holder for commutators having a brush engaging face; a brush having a groove therein slidably engaging the face and the commutator, and means on the face 20 fitting within the groove for guiding the brush toward and from the commutator.
3. A brush holder for commutators having a brush engaging face; a brush having a groove therein slidably engaging the face and the commutator, and a rib on the face 25 fitting within the groove for guiding the brush toward and from the commutator.
4. A brush holder for commutators having a plate mounted thereon for adjustment toward and from the commutator, and a brush slidably engaging the plate and 30 the commutator.
5. A brush holder for commutators having an element mounted thereon for adjustment 35 toward and from the commutator, and a brush slidably engaging the element and the commutator.
6. A brush holder for commutators having a brush engaging element mortised 40 thereto and adapted to be adjusted from one mortised position to another; means for

holding the element in a mortised position, and a brush slidably engaging the element and the commutator.

7. A brush holder for commutators including a bracket having teeth thereon; a brush engaging element having parts meshing with the teeth and adapted to be adjusted from one meshing position to another; means for holding the element in adjusted 45 position; a brush slidably engaging the element and the commutator, and means on the bracket for holding the brush in position.

8. A brush holder for commutators having a brush engaging plate mortised thereto and adapted to be adjusted from one mortised position to another; means for holding the plate in a mortised position, and a brush 50 slidably engaging the plate and the commutator.

9. A brush holder for commutators having a brush engaging plate mounted thereon for adjustment toward and from the commutator; a brush slidably engaging the plate and the commutator, and means on the 55 plate for guiding the brush toward and from the commutator.

10. A brush holder for commutators having a brush engaging plate mounted thereon for adjustment toward and from the commutator; a brush slidably engaging the plate and the commutator, and a rib on the plate 60 for guiding the brush toward and from the commutator.

In testimony whereof we have signed our 75 names to this specification in the presence of two subscribing witnesses.

ALEXANDER W. FARCUS.
DAVID T. JACOBS.
